WILLIAM CULLINANE
INVENTOR:

By Ottawan

his ATTORNEY.

UNITED STATES PATENT OFFICE.

WILLIAM CULLINANE, OF BRISTOL, ENGLAND.

HENCOOP AND THE LIKE.

Application filed November 10, 1924. Serial No. 748,966.

To all whom it may concern:

Be it known that I, WILLIAM CULLINANE, of Bristol, England, a subject of the King of Great Britain and Ireland, have invented 5 certain new and useful Improvements in or Relating to Hencoops and the like, of which the following is a specification.

This invention relates to hen coops and the like.

10 The object of my invention is to provide an improved coop.

A hen coop or the like made in accordance with this invention comprises a case member, a canopy member, preferably wire, 15 pivoted thereto so that it can be let down in front of the case member to form a run or folded back over or under the case member as required, and a partition member adapted to divide the case member from the run.

20 Preferably, the coop comprises a case having a rectangular front and bottom and quadrantal sides; pivoted to and disposed within the case is a hood with quadrantal sides and a wire-work canopy; the front of 25 the case is provided with a cover at the top.

Referring to the accompanying drawings, which illustrate one form of device made in accordance with my invention;

30 Fig. 1 is a perspective view of the coop closed;

Fig. 2 is a perspective view showing the wire-work door or partition member lowered;

35 Fig. 3 is a perspective view showing the canopy lowered in front; and

Fig. 4 is a perspective view showing the front door used as a shelter from the weather.

40 In the drawings, the hen coop is provided with a case *a* having a rectangular front *b* and bottom *c* and quadrantal sides *d*. Within the case *a* is a hood *e* with quadrantal closed in sides *e'* and a wire-work canopy *f*. The hood is pivoted at *g*. The front of the case *a* has a cover *h* hinged to it at the top *j* so as to close the case *a* or to 45 form a sunshade to the hood *e* when the hood is open, or to be folded back to lie on the casing. At the front, the case *a* is provided with a hinged wire-work gate or partition member *k*, adapted to be folded down to allow the hen to get out, but when folded up will allow the chicks to pass in and out

but prevent the hen getting out. The front of the casing *a* is provided with stays *m* 55 having rings *n* to which the cover can be secured when closed down onto the casing. Ventilation holes *o* are provided in the casing *a*, quadrantal sides *c'* of the hood *e* and cover *h*. The canopy *f* is stoutly constructed 60 of the best made-up wire and galvanized after construction. The coop itself is very stoutly constructed of the best galvanized sheets and has a loose wooden floor *p*. Handles *q* are provided at the sides of the coop. 65

In use, the cover *h* is folded back, the hinged gate *k* folded down and the hen placed in the coop; the gate *k* is then closed and secured to the stays *m* by rings *n*, or otherwise. If it is desired for chicks to be 70 enclosed, the hood *e* is turned on its hinge *g* outwards and downwards so as to enclose a space in front of the coop and form a run for the chicks. The cover *h*, and if desired the case *a*, are ventilated by holes *o* so that 75 when closed in, plenty of air circulates in the coop.

The coop affords complete immunity from rats, cats, foxes and the like to the hens and chicks, not only during the night-time 80 when closed (see Fig. 1) but also during the day-time when the run is folded out to allow the chicks to have the benefit of the run. It is only the work of a moment to move the coop to fresh, sweet grass. 85

What I claim and desire to secure by Letters Patent is:—

1. A coop comprising in combination a case member, a canopy member pivoted to said case member, means whereby the canopy member can be let down in front of the case to form a run, and a partition member hinged to move as a whole and adapted to divide the case member from the run. 90

2. A coop comprising in combination a case member, a canopy member pivoted to said case member, means whereby the canopy member can be let down in front of the case to form a run and a partition member hinged to move as a whole and adapted 95 to divide the case member from the run, and a cover hinged at the top. 100

In testimony whereof I have signed my name to this specification.

WILLIAM CULLINANE.
